(57) **CLAIM**

The ornamental design for a LED light bulb string, as shown and described.

DESCRIPTION

FIG. 1 is perspective view of a first embodiment of a LED light bulb string showing my new design;

FIG. 2 is a perspective view thereof;

FIG. 3 is a front view thereof;

FIG. 4 is a back view thereof;

FIG. 5 is left side view thereof;

FIG. 6 is a right side view thereof;

FIG. 7 is a top view thereof;

FIG. 8 is a bottom view thereof;

FIG. 9 is a perspective view of a second embodiment;

FIG. 10 is a perspective view thereof;

FIG. 11 is an enlarged detailed perspective view of area 11 in FIG. 1;

FIG. 12 is an enlarged detailed perspective view of area 12 in FIG. 1;

FIG. 13 is an enlarged detailed perspective view of area 13 in FIG. 1;

FIG. 14 is an enlarged detailed perspective view of area 14 in FIG. 2;

FIG. 15 is an enlarged detailed perspective view of area 15 in FIG. 2; and,

FIG. 16 is an enlarged detailed perspective view of area 16 in FIG. 2.

The broken lines depict portions of the LED light bulb string, the dash-dot-dash broken lines encircling the enlarged views in FIGS. 1-2, 11-16 are for annotation purposes only; all broken lines form no part of the claim. The LED light bulb string is shown with a symbolic break in its length. The appearance of any portion of the article between the break lines forms no part of the claimed design. S shaped double solid lines in FIGS. 1-4 and 7-10 depict a symbolic break to indicate an indeterminate length. Appearance of any portion between the S shaped double solid lines forms no part of the claimed design.
